UNITED STATES PATENT OFFICE

166,994

GLASS ASH TRAY

Louis Poglein, Jeannette, Pa., assignor to McKee
Glass Company, Jeannette, Pa., a corporation
of Pennsylvania

Application October 2, 1951, Serial No. 16,807

Term of patent 14 years

(Cl. D85—2)

To all whom it may concern:

Be it known that I, Louis Poglein, a citizen of the United States, residing at Jeannette, county of Westmoreland, and State of Pennsylvania, have invented a new, original, and ornamental Design for Glass Ash Tray, of which the following is a specification, reference being had to the accompanying drawing, forming a part hereof. In the drawing,

Fig. 1 is a top plan view of a glass ash tray, showing my new design;

Fig. 2 is a cross-sectional view taken through the center line of Fig. 1;

Fig. 3 is a bottom plan view thereof; and
Fig. 4 is a perspective view thereof.

I claim:

The ornamental design for a glass ash tray, substantially as shown.

LOUIS POGLINE.
